No. 761,608.

PATENTED MAY 31, 1904.

C. M. RHODES.
SASH LIFTER.

APPLICATION FILED FEB. 26, 1903.

NO MODEL.

Fig. 2.

Fig. 1.

UNITED STATES PATENT OFFICE.

CHARLES M. RHODES, OF STEUBENVILLE, OHIO.

SASH-LIFTER.

SPECIFICATION forming part of Letters Patent No. 761,608, dated May 31, 1904.

Application filed February 26, 1903. Serial No. 145,268. (No model.)

To all whom it may concern:

Be it known that I, CHARLES M. RHODES, a citizen of the United States of America, residing at Steubenville, in the county of Jefferson and State of Ohio, have invented certain new and useful Improvements in Sash-Lifters, of which the following is a specification, reference being had therein to the accompanying drawings.

10 My invention relates to certain new and useful improvements in sash-lifters, and aims to produce a simultaneous action or movement of the upper and lower sash in reverse directions when one or the other is actuated. I 15 also propose to provide for the independent movement of either the upper or lower sash, whereby one or the other may be raised or lowered without creating any movement whatever on the opposite one.

20 In detail the further and other various objects of the invention will readily appear in the specification and drawings.

In the drawings, Figure 1 represents a transverse section of one end of the window-frame, 25 showing the upper and lower sash also in section and partly broken away. Fig. 2 is a sectional view on the line 2 2 of Fig. 1. Fig. 3 is a section on the line 3 3 of Fig. 2, and Fig. 4 is a detailed perspective view of the sliding 30 plate.

The upper sash is designated at 1 and the lower sash at 2. 3 designates the parting-bead, and 4 the guide-strip located on the outside of the window-frame 5, and 6 designates the inner 35 guide-strip, which, as is well known, is usually ornamented by beading.

40 Embedded within the window-frame is a casing 6 of substantially rectangular form and located so as to extend in alinement with the upper and lower sash. Journaled within this casing is a shaft 7, whose ends may be 45 suitably secured in the ends of the casing and which is adapted to have a relatively fixed position. Freely mounted upon this shaft 7 are 50 gear-wheels 8 9, which project through slotted portions 10 11 in the side of the casing 6 and which are adapted for engagement with racks 12 13, embedded in and suitably secured to one side of the upper and lower sash. These 55 gears are adapted to at all times mesh with

the said racks and when suitably actuated will impart movement thereto, and thereby impart movement to the upper and lower sash. The gear-wheel 9 has fixedly secured thereto a beveled pinion 14, which under normal conditions 55 is in mesh with a beveled gear-wheel 15, carried on a shaft 16. This beveled pinion is keyed to the shaft 16 and is adapted to partake of all of the movements thereof whether rotary or in a horizontal plane. This shaft 60 16, for a purpose to be hereinafter referred to, has movement in a horizontal plane, and to effect this I secure to one end of the shaft a bearing 17, which is slidably mounted in guideways 18 19, formed with in turned flanges 65 20 21, these guideways being in fixed relation to the side of the casing 6. The opposite end of the shaft 16 is suitably secured, as at 22, to a sliding plate 23, adapted to move in a horizontal plane within guideways 24 25, carrying 70 inturned flanges 26 27, substantially identical with those within which the bearing 17 may move. This sliding plate, as will be perceived from Fig. 4 of the drawings, may be of a substantially rectangular form and is provided with a slot 24 to readily permit the gear-wheel 9 to protrude therethrough, this slot being of sufficient width to permit of a horizontal play of the plate 23 without the plate contacting with the gear-wheel 9. I 80 85 may also form a guideway 28 on the one end of the casing 6, as shown, which will provide a more perfect guide for the sliding plate. As will be seen from Fig. 3 of the drawings, the shaft 16 lies substantially in the same plane as the shaft 7, and in order to effect this I provide the shaft 16 with a somewhat enlarged portion 29, suitably bored, as at 30, to freely receive the shaft 7, and thus in no wise interfering with the movement of the latter. 90

Rigidly secured to the gear-wheel 8 is a disk 30, carrying teeth 31, adapted for engagement with teeth of a similar form (designated at 32) carried by the beveled pinion 33, freely mounted on the shaft 7. It will be 95 noted from Fig. 1 of the drawings that the teeth 32 are so positioned as to engage the teeth 31, and the beveled gear-wheel 15 being in mesh with the pinion 33 and pinion 14, the latter having suitable connection with the 100

lower sash and the teeth 31 through the medium of disk 30, the gear-wheel 8 of the rack 12 having suitable connection with the upper sash, any movement imparted to the beveled pinion 15 through the medium of either sash will create a reverse movement upon the opposite sash by virtue of the mechanism just described.

However, at times it is found convenient to 10 actuate either the upper or lower sash independent of the other, and in order to permit of this desideratum the plate 23, which, as just stated, having connection with the shaft 16, is slid inwardly through the medium of a 15 rod 34, secured thereto for this purpose and which is suitably enlarged to form a hand-grip 35 at its outer end, this inward movement of the sliding plate carrying beveled gear-wheel 15 inwardly out of engagement with the beveled pinion 14, movement of this wheel 15 being permitted by reason of the play existing 20 between the teeth 31 of disk 30 and teeth 32 of beveled pinion 33. When in this position, either the upper or lower sash may be raised 25 or lowered, as desired, and this movement will not affect the opposite sash.

The gear-wheel 9 is provided with a series 30 of circumferentially-arranged apertures, (dotted lines, Fig. 1,) adapted to receive a protruding pin 36, carried on one end of the locking-rod 37, provided with a hand-grip 38, this rod 37 carrying a collar 39, secured in a depressed portion 40 in the inner end of the casing 6, this rod 37 when slid inwardly causing this 35 pin 36 to engage in one of the said apertures, and thereby lock the gear-wheel 9. This gear-wheel may be locked at any position desired, and a multiplicity of apertures may be formed therein in order to permit of various adjustments of the gear-wheel 9. In order to provide for a suitable locking of the opposite gear—namely, 8—this is also formed with a 40 series of circumferentially-arranged apertures adapted to receive a pin 41, carried on the 45 end of the sliding plate, this pin only engaging in the apertures when the plate is thrown the full distance, such as will be permitted by the distance between the ends of the teeth 32 and the bottom walls formed by the teeth 31 50 of the disk 30. In throwing this beveled wheel 15 inwardly sufficient to disengage its teeth from those of the beveled pinion 14 the pin 41 will not be thrown sufficiently to engage in the apertures of the gear-wheel 8, and 55 this is effected by throwing the sliding plate 23 its full distance.

The invention as illustrated in the accompanying drawings is susceptible to many changes and alterations which will not depart from the spirit and scope of my invention as evidenced thereby, and I therefore do not desire to be restricted to any details illustrated which can be readily altered.

Having thus fully described my invention, what I claim as new, and desire to secure by Letters Patent, is—

1. A device of the type set forth, consisting of gear-wheels independently mounted, a beveled pinion secured to one of said gear-wheels, a toothed disk secured to the other of 70 said gear-wheels, a beveled pinion carrying teeth adapted for engagement with the said toothed disk, a beveled gear-wheel meshing with said beveled pinions, and means for throwing said beveled gear-wheel in a horizontal 75 plane.

2. A sash-lifter comprising a separate gear for actuating each sash, a separate beveled pinion for each actuating-gear, a shaft on which one of said pinions is fixed, and the other is 80 loosely mounted, a gear interposed between and in mesh with each of said pinions, and means for shifting the bevel-gear out of engagement with the pinion fixed on the shaft and simultaneously locking the loosely-mounted 85 pinion to the shaft.

3. In a device of the type set forth, a gear for actuating each sash, a pinion for actuating each gear, means interposed between and normally in engagement with each of said pinions for simultaneously actuating the same, and means to permit said pinion-actuating 90 means to be disengaged from one of said pinions.

4. A sash-lifter comprising an actuating-gear for engaging each sash, and a pinion operatively connected to each gear, a shaft mounted for slidable horizontal movement, and a bevel-gear on said shaft normally meshing with both pinions, means for shifting the shaft 100 and thereby the bevel-gear to disengage the said gear from one of the pinions while maintaining its engagement with the other pinion, and means for locking the actuating-gears 105 against movement.

In testimony whereof I affix my signature in the presence of two witnesses.

CHARLES M. RHODES.
